No. 36,888.

Patented April 26, 1904.

UNITED STATES PATENT OFFICE.

ALFRED SCHICKERLING, OF NEW YORK, N. Y., ASSIGNOR TO SCHICKERLING BROTHERS AND COMPANY, OF NEW YORK, N. Y., A FIRM.

DESIGN FOR A BADGE OR SIMILAR ARTICLE.

SPECIFICATION forming part of Design No. 36,888, dated April 26, 1904.

Application filed April 17, 1903. Serial No. 153,146. Term of patent 7 years.

To all whom it may concern:

Be it known that I, ALFRED SCHICKERLING, a citizen of the United States, and a resident of New York, borough of Manhattan, in the county of New York and State of New York, have invented a certain new, original, and ornamental Design for a Badge or Similar Article, of which the following is a specification.

The accompanying drawing shows in perspective a badge having my design applied thereto.

What I claim is—

The ornamental design for a badge or similar article, as shown.

Signed at New York, borough of Manhattan, in the county of New York and State of New York, this 14th day of April, A. D. 1903.

ALFRED SCHICKERLING.
